Specification for Design.

Patented Sept. 19, 1911.

Application filed January 16, 1911. Serial No. 603,022. Term of patent 14 years.

To all whom it may concern:

Be it known that I, BERT O. TILDEN, a citizen of the United States, residing at New York, in the county of New York and State of New York, have invented a new, original, and ornamental Design for a Water-Closet Bowl, of which the following is a specification, reference being had to the accompanying drawing, forming a part thereof.

Figure 1 is a perspective view of a water-

closet bowl, showing my new design. Fig. 2 is a front elevation of the bowl.

I claim:

The ornamental design for a water-closet bowl, as shown.

BERT O. TILDEN.
